UNITED STATES PATENT OFFICE.

LUKE W. FARMER, OF SOMERVILLE, MASSACHUSETTS.

PAPER CARTON.

1,224,726.

Specification of Letters Patent.

Patented May 1, 1917.

Application filed March 4, 1914. Serial No. 822,259.

To all whom it may concern:

Be it known that I, LUKE W. FARMER, a citizen of the United States, residing at Somerville, in the county of Middlesex and 5 State of Massachusetts, have invented an Improvement in Paper Cartons, of which the following is a specification.

This invention relates to paper-cartons adapted to contain milk, oysters, and other 10 liquid and semi-liquid substances, as well as solids, and the invention resides particularly in the top-closure of the carton, and so far as my present invention is concerned, the 15 form of the body of the carton and its bottom-closure may be of any well-known or suitable construction.

The invention has for its object the construction of the paper carton having a top-closure which is liquid tight and which is 20 arranged to avoid the production of a recess or well at the top of the carton which is very objectionable.

The top-closure embodying this invention involves the construction of the upper end- 25 portion of the body and also of a closing-cap. My invention is susceptible of certain modifications, as will be described.

Figure 1 is a side-elevation and partial 30 section of a paper-carton having a top-closure embodying this invention.

Figs. 2 and 3 are similar views of modified forms of the invention.

Referring to Figs. 3, 10 represents the body of the carton which is composed of 35 thick, heavy paper, such as tag-stock for instance, and which may be made cylindrical or frusto-conical, as desired. The upper end-portion of said body is formed near its edge, with an outwardly extended corrugation, which is arranged circumferentially entirely around it, thereby to form on the interior of the body a circumferential groove or recess 12 at the bottom of a short vertical portion 13, and on the exterior of the 40 body a circumferential rib 14. The closing-cap, in the simplest form of the invention here shown, consists of a thick circular disk of heavy fiber-board or paper-board, which may be composed of numerous thin 45 layers of paper adhesively secured together to form a solid structure or mass of great hardness and density. Said disk is made of a thickness corresponding to the distance between the upper edge of the body and the 50 lower side of the groove or thereabout, and its edge is formed by cutting or otherwise 55

to exactly conform to the interior of the upper end-portion of the body, said edge having a vertical portion corresponding to the vertical portion 13 between the upper edge 60 of the body and the top of the groove and having an outwardly curved portion corresponding to the shape and dimensions of the groove 12, so that said disk when thrust into the top of the body will engage the interior wall thereof at the upper end-portion and form a tight joint thereat. It will be understood that while the body is composed of paper which is thick and heavy, yet will 65 have some resiliency, enabling it to yield 70 and admit of the curved projecting rib on the disk passing the short vertical portion and then to assume its normal position and engage the edge of the vertical portion of the disk when the projecting rib thereon 75 has entered the groove in the body. When the disk is sprung into place its top surface occupies a position flush with the upper edge of the body, so that no recess or well is produced at the top of the carton. In a modified form of my invention, see Fig. 2, a circular disk 20 is adhesively or otherwise secured to the top of said disk, which is made of larger diameter, so that its edge-portion 80 extends over the upper edge of the body, but, in view of the tight joint produced by the engagement of the disk with the body said supplementary disk is not of great importance.

In another modification of my invention, 90 see Fig. 1, a supplementary circular disk 30 having a flange 31 at its edge is adhesively or otherwise secured to the top of the disk and said flange is arranged to engage the exterior of the body, and to extend over and engage the outwardly extended curved rib on the exterior thereof. This form of the invention, like the aforesaid modification, is 95 not of great importance, in so far as forming a tight joint is concerned, although these supplementary pieces may be easily and economically printed upon, so as to serve as an advertising medium. If employed, however, they should be made of substantially 100 the dimensions here shown, as compared with the body, so as not to present projecting edges.

I claim:

1. A carton including a paper body formed 110 near its upper end portion to provide on the interior of the body an annular channel, and a portion above the channel in parallelism

- with the axial line of the body, and a disk of substantially uniform thickness having an annular edge projection coincident with the lower surface of the disk to fit the channel and the body, the edge surface of the disk above said projection being at right angles to the surface of the disk to fit throughout that portion of the body above the annular channel.
- 10 2. A carton including a paper body formed on the interior near the upper end thereof with an annular channel, a disk having an edge portion formed to seat in the channel, that portion of the disk above the edge portion, and the corresponding portion of the

body above the channel being arranged for engagement and being disposed in parallelism with the axis of the body, and a second disk secured to the first mentioned disk and projecting beyond the edge of the latter to 20 provide a portion to engage the upper edge of the body when the first mentioned disk is in seating condition therein.

In testimony whereof, I have signed my name to this specification, in the presence of 25 two subscribing witnesses.

LUKE W. FARMER.
